(57) **CLAIM**

The ornamental design for a cover for electronic communications device, as shown and described.

DESCRIPTION

FIG. 1 is a front perspective view of a cover for electronic communications device showing my new design; FIG. 2 is a rear perspective view of the cover for electronic communications device of FIG. 1;

FIG. 3 is a front elevation view of the cover for electronic communications device of FIG. 1;

FIG. 4 is a rear elevation view of the cover for electronic communications device of FIG. 1;

FIG. 5 is a side elevation view of the cover for electronic communications device of FIG. 1;

FIG. 6 is an opposite side elevation view of the cover for electronic communications device of FIG. 1;

FIG. 7 is a top plan view of the cover for electronic communications device of FIG. 1; and,

FIG. 8 is a bottom plan view of the cover for electronic communications device of FIG. 1.

The broken lines immediately adjacent the shaded regions represent the bounds of the claimed design. All other broken lines depict environmental subject matter that forms no part of the claimed design. The broken lines and unshaded regions bounded by broken lines form no part of the claimed design.
